UNITED STATES PATENT OFFICE.

BENJMAN A. STODDARD, OF MOSHERVILLE, MICHIGAN, ASSIGNOR OF ONE-HALF TO ROMONDO DAVIS, OF ALBION, MICHIGAN.

STAY-WIRE-ATTACHING DEVICE.

SPECIFICATION forming part of Letters Patent No. 631,681, dated August 22, 1899.

Application filed January 6, 1899. Serial No. 701,356. (No model.)

To all whom it may concern:

Be it known that I, BENJMAN A. STODDARD, a citizen of the United States, residing at Mosherville, in the county of Hillsdale and State of Michigan, have invented a new and useful Fence-Machine, of which the following is a specification.

My invention relates to improvements in machines for applying stay-wires to horizontal strand-wires for the fabrication of a wire fence in the field; and the primary object of the invention is to provide a simple structure by which the stay-wire may be securely interlocked or twisted around the horizontal strand-wires rapidly and easily.

A further object is to provide an improved construction of the machine in which provision is made for readily taking out an empty bobbin or spool and for replacing the same with a filled bobbin, and also to permit the bobbin to rotate freely within the supporting means by which it is securely held against displacement.

A further object of the invention is to provide means for holding the horizontal wires during the application of the stay-wire thereto, and which also serves to space the stay-wires in their application to the horizontal strand-wires.

With these ends in view the invention consists in the novel combination of elements and in the construction and arrangement of parts, which will be hereinafter fully described and claimed.

To enable others to understand the invention, I have illustrated the same in the accompanying drawings, forming a part of this specification, and in which—

Figure 1 is an elevation of a part of a fence with my spacing device applied thereto and showing the machine in operative position. Fig. 2 is a perspective view of the machine on an enlarged scale. Fig. 3 is a longitudinal sectional view through the machine, represented by Fig. 2. Fig. 4 is a transverse section through the machine on the plane indicated by the dotted line 4-4 of Fig. 3. Fig. 5 is an enlarged perspective view of the spacing device.

Like numerals of reference denote like and

corresponding parts in each of the several figures of the drawings.

The stay-wire-applying machine 10 of my invention has a head-block 11, which may be cast or otherwise formed in a single piece. 55 This head-block is provided with a threaded opening 12, and near one end it is furthermore provided with a transverse bolt-hole 13. A tubular needle 14 of any desired length is provided at one end with a reduced or conical extremity 15, and its other end or heel has a male thread 16^a, adapted to be screwed firmly into the threaded opening 12 of the head-block, whereby the needle is firmly and detachably united to the head-block, and it 65 opens through the latter for the free passage of the wire from a bobbin or spool. A pair of supporting-plates 16 17 are arranged in parallel positions on one side of the head-block, and these supporting-plates are offset 70 at points intermediate of their length, as at 18, to provide a space of sufficient width for the accommodation of the supply spool or bobbin. The front ends of the plates are perforated, as at 19, and they are arranged 75 to overlap the perforated part 13 of the head-block, so that the openings in the supporting-plates will be coincident with the hole 13 in the head-block for the reception of a bolt 20, that serves to firmly and detachably fasten 80 the supporting-plates to the head-block. The supporting-plates have inwardly-extending flanges 21 at their separated ends, and on the opposing faces of these plates are provided cylindrical bosses 22, that lie in coincident positions and form the journals for the spool or bobbin 23. This spool is designed to carry the wire that forms the stay for the fence, and it is constructed with a tubular arbor 24, which opens through the heads of the spool in order 85 that the journals 22 of the supporting-plates may be readily fitted thereto.

In applying the stay-wires to a fence it is frequently necessary to remove an empty bobbin or spool in order that a filled bobbin 95 may be carried by the machine, and my construction provides for the ready interchange of the bobbins. It is evident that the supporting-plates may be sprung apart or the bolt 20 loosened for the separation of the 100

plates, so as to withdraw the journals 22 from the ends of the tubular spool-arbor, thus enabling the spool when empty to be taken out of the machine. A filled spool may now be placed in position between the plates for the journals to enter its arbor and the bolt 20 may be tightened for the purpose of clamping the supporting-plates firmly to the head-block. The supporting-plates serve to sustain the spool or bobbin in proper relation to the tubular needle 14 for the wire to be led from the spool into and through the needle, and this bobbin is mounted idly on the journals, so as to rotate with freedom and ease thereon.

In connection with my machine for applying the stay-wire to the horizontal strand-wires I employ a standard or bar 25 for the purpose of supporting the strand-wires at the places where the stay is to be intertwined or united therewith, and this standard is equipped with means which serve to indicate the proper spacing of the stay-wires in applying the latter to the strand-wires. The standard is equipped with a series of collars 26, each of which is provided with a socketed boss 27, that receives the binding-screw 28, adapted to impinge against the standard for the purpose of adjustably clamping the collars 26 in the desired position on the standard. The upper end of the standard has a hook-shaped plate 29, which may be fitted on the upper horizontal wire of the fence for the purpose of suspending the standard or bar, whereby the collars 26 may engage with the horizontal strand-wires for the purpose of supporting them in their proper spaced relations. The collars may be grouped in any desired positions on the standard—that is to say, they may be spaced at uniform distances apart—but I prefer to group the collars at the lower part of the standard more closely together than the collars at the upper part of the standard, as shown by Figs. 1 and 5, for the purpose of arranging the wires at the lower part of the fence quite close together, and thereby prevent small stock from passing through the fence. The standard 25 also supports a spacing-arm 30, which is attached to a collar 31, that is fitted on the standard at a point intermediate of its length and is equipped with a binding-screw 32, which serves to hold the collar and the spacing-arm in proper position on the standard. The spacing-arm is equal in length to the distance between two adjoining stay-wires, and the arm serves to indicate the distance of the standard from the previously-applied stay-wire, whereby the stay-wires may be united to the horizontal strands at regular intervals. The operation may be described as follows: The horizontal strand-wires are first stretched between the posts, and they are arranged at the desired intervals apart. The collars 26 on the standard 25 are spaced correspondingly to the strand-wires, and they are secured firmly to the standard by their bind-

ing-screws 28. A filled spool or bobbin is introduced between the plates of the weaving-machine for the journals 22 to enter the tubular arbor, and thereby loosely support the spool in position, and the unconfined end of the wire from this spool is threaded or drawn through the tubular needle. The standard 25 is applied at the proper place to the horizontal strand-wires for the hook-shaped plate 29 to engage with the upper wire and the collars 26 to support the intermediate and bottom wires. The machine 10 is now used to supply the wire which is twisted around the strand-wires to form the stay 34, and this machine is first operated to connect one end of the wire from its bobbin to the bottom strand-wire, thence to the second strand-wire, and so on throughout the series. In using the machine it is held by the supporting-plates 16 17 in one hand of the operator for the needle 14 to rest on the strand-wire in a position oblique to its length, substantially as indicated by Fig. 1, and the machine is carried or moved around the strand-wire for the purpose of intertwining or interlocking the wire from the bobbin with the strand-wire. In my invention the machine may be moved from left to right, or vice versa, from right to left, for the intertwining of the stay-wire with the strand-wires, and the two wires are united together by an interlocking joint, which renders it necessary to carry the machine only once around each strand-wire. It will be understood that the stay is united to the strand-wires at the points where the latter engage with the collars of the standard 25, and the employment of the tubular needle enables the machine to be held and operated at one side of the standard, while the stay-wire passes from the bobbin through the tubular needle in order that it may be united properly with the strand-wires at the points where the latter are engaged with the collars. The ends of the stay are secured firmly to the top and bottom strand-wires, and after the stay has been applied to the wires it may be severed from the length of wire on the bobbin. The standard 25 is now shifted along the strand-wires for a distance equal to the length of the arm 30, the end of which should be placed opposite to the line where the stay-wire is previously applied to the strands, and the operation of applying another stay-wire to the strands is repeated.

Changes may be made in the form and proportion of some of the parts, while their essential features are retained and the spirit of the invention embodied. Hence I do not desire to be limited to the precise form of all the parts as shown, reserving the right to vary therefrom.

Having thus described the invention, what I claim is—

1. A stay-wire-applying implement provided with a tubular needle, and with a revolvable bobbin supported contiguous to the heel of said needle and arranged to supply a wire

continuously thereto, whereby the implement may be positioned for the needle to lie obliquely to the line-wire in applying the stay thereto.

on the plates and removable at will therefrom, substantially as described. 20

5. A fence-machine consisting of a head-block, the supporting-plates arranged parallel to each other, fastened detachably to the head-block and provided on their opposing faces with the journals, a spool or bobbin fitted between the plates and having a hollow arbor which receives the journals, and an elongated tubular needle fast with the head-block, substantially as described.

In testimony that I claim the foregoing as my own I have hereto affixed my signature in the presence of two witnesses. 30

BENJMAN A. STODDARD.
